(57) CLAIM

The ornamental design for a bottle shaped telephone handset, as shown and described.

DESCRIPTION

FIG. 1 is a back view of the bottle shaped telephone handset.

FIG. 2 is a front view of the bottle shaped telephone handset.

FIG. 3 is a top view of the bottle shaped telephone handset.

FIG. 4 is a bottom view of the bottle shaped telephone handset.

FIG. 5 is a right side view of the bottle shaped telephone handset; and,

FIG. 6 is a left side view of the bottle shaped telephone handset.

The broken lines are for environmental purposes only and form no part of the claimed design.
